US00D864166S

(12) **United States Design Patent** (10) **Patent No.:** **US D864,166 S**
You (45) **Date of Patent:** **** Oct. 22, 2019**

(54) **HEADSET**

(71) Applicant: **DONGGUANG TINGBEI ELECTRONIC TECHNOLOGY CO., LTD.**, Dongguang, Guangdong (CN)

(72) Inventor: **Pei You**, Dongguang (CN)

(73) Assignee: **DONGGUANG TINGBEI ELECTRONIC TECHNOLOGY CO., LTD.**, Dongguang, Guangdong (CN)

(**) Term: **15 Years**

(21) Appl. No.: **29/653,196**

(22) Filed: **Jun. 13, 2018**

(51) **LOC (12) Cl.** **14-01**

(52) **U.S. Cl.**

USPC **D14/223**

(58) **Field of Classification Search**

USPC D14/223, 205; D24/174; 128/865, 866, 128/867; 181/129, 130, 135; 379/430, 379/431; 381/380, 381, 322, 328, 329;

455/90.3, 575.1, 569.1

CPC H04R 1/10; H04R 25/00; H04R 25/02; H04R 1/1041; H04R 1/05; H04R 1/1016; H04R 1/1066; H04R 5/033; H04R 5/0335

See application file for complete search history.

(74) *Attorney, Agent, or Firm* — Juan Carlos A. Marquez; Marquez IP Law Office, PLLC

(57) **CLAIM**

The ornamental design for a headset, as shown and described.

DESCRIPTION

FIG. 1 is a perspective view of a headset, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

1 Claim, 7 Drawing Sheets
